UNITED STATES PATENT OFFICE.

FRANCIS SEYMOUR, OF PATERSON, NEW JERSEY, ASSIGNOR TO THE AUTOMATIC COMPANY, OF NEW YORK, N. Y.

STOP-MOTION FOR SPINNING-MACHINES.

SPECIFICATION forming part of Letters Patent No. 552,149, dated December 31, 1895.

Application filed February 24, 1890. Serial No. 341,482. (No model.)

To all whom it may concern:

Be it known that I, FRANCIS SEYMOUR, of Paterson, Passaic county, State of New Jersey, have invented a new and useful Improvement 5 in Stop-Motions for Spinning Mechanism, of which the following is a full, true, and exact description, reference being had to the accompanying drawing.

This invention relates to an improvement 10 in stop-motions in spinning mechanisms for spinning, doubling and respinning silks or other fibers which are frictionally driven from a friction-wheel, its object being to provide means for automatically checking the 15 spinning process should the thread be broken through any cause.

My invention will be readily understood from the accompanying drawing, in which—

A represents the driving-shaft; B, the friction-wheel; C, a spindle or spindles driven from the wheel B by a friction-wheel D. The friction-wheel D is mounted upon a frame having a horizontal pivot E and is over-weighted so as to normally fall away from contact with the driving-wheel B. It is held in contact by spring F. The spring F is held in its stretched position by hook G hooking upon plate H. In the operation of such spinning mechanisms the thread passes from the bobbin through the faller-eye K to spindle C and is wound thereon by the motion communicated through shaft A and friction-wheels B and D. The thread from the spindle C passes through faller-eye K. When the thread breaks, the

faller-eye K falls in contact with the lever L 35 pivoted to hook G, as shown, thereby depressing the outward end of said lever. The shaft A is provided with cam M, which ordinarily does not strike the inward end of lever L; but when said inward end is raised the cam M 40 strikes the same, releases the hook G from the plate H, and thereby releases the tension of the spring, allowing the friction-wheel D to fall out of contact with the driving-wheel B.

What I claim as my invention, and desire 45 to secure by Letters Patent, is—

The combination of the driving shaft A, the driving wheel B attached to the shaft, the cam M also attached to the shaft, the wheel D driven frictionally from the driving wheel, 50 the pivoted frame supporting said wheel D, the spring F holding the wheels B and D in contact, the faller eye K through which a thread runs, the hooked lever G, and the two armed lever L pivoted to the lever G and having one 55 of its arms normally standing in the path of the faller eye when it falls and being depressed thereby its opposite arm being brought, by said depression, into the path of cam M. and engaged and moved thereby to release the tension of spring F., substantially as described. 60

In testimony whereof I have signed my name to this specification in the presence of two subscribing witnesses.

FRANCIS SEYMOUR.
